MULTIPLE IMPRESSION PRINTING MEANS

Walter E. Hamlin, Cleveland, Ohio, assignor to
The Cleveland Shopping News Company,
Cleveland, Ohio, a corporation of Ohio

Application May 9, 1935, Serial No. 20,600

6 Claims. (Cl. 270—5)

In successive impression or multiple color work, heretofore it has been customary to examine samples of the finished product at the delivery table of the press and then go back and apply correction 5 of register at the respective printing points. This incurs considerable lag in attaining necessary correction and also occasions waste which may be considerable in high speed presses. A quicker way of obtaining corrective adjustment has long been 10 desired, and particularly it is desirable to know the condition of the work before it goes to final folding. In accordance with the present invention, this now becomes possible.

To the accomplishment of the foregoing and related ends, the invention, then, comprises the features hereinafter fully described, and particularly pointed out in the claims, the following description and the annexed drawings setting forth in detail certain illustrative embodiments of the 20 invention, these being indicative however, of but a few of the various ways in which the principle of the invention may be employed.

In said annexed drawings:—

Fig. 1 is a schematic side elevational view of 25 printing press mechanism embodying the invention; Fig. 2 is an enlarged transverse section thereof taken on a plane substantially indicated by a line II—II, Fig. 1; Fig. 3 is an enlarged elevational detail; Fig. 4 is a sectional detail on further enlarged scale; Fig. 5 is a wiring diagram; Fig. 6 is a vertical section taken on a plane substantially indicated by line VI—VI, Fig. 2; Fig. 7 is an enlarged sectional detail taken on a plane substantially indicated by line VII—VII, Fig. 6; 30 Fig. 8 is a section taken on a plane substantially indicated by line VIII—VIII, Fig. 7; and Fig. 9 is a transverse section taken on a plane substantially indicated by line IX—IX, Fig. 2.

In its general aspects, the invention contemplates 40 a plurality of successive impression means of usual or desired character, involving printing, lithographing, scoring, embossing, multi-color cylinders, etc., and register means including means for vising or viewing, and means for selectively setting the relative adjustment between the sheet material being printed and the impression surfaces. In the form shown in the drawings, there is a press mechanism including color cylinders A, B, C, through which a web of paper P 45 feeds successively, and thence to black printing cylinders D, E. From the latter, the paper web is directed to the folding and cutting end of the machine, including folding rolls 2, 3, cutter rolls 4, and delivery rolls 5. Positioned at a point 50 subsequent to the last impression to be registered,

is a vising means which provides instantaneous glimpses of the rapidly moving paper web, such glimpses being timed in synchronism with the speed of the web, such that irrespective of its actual linear velocity, the view of the impressed 5 traveling web appears to the operator as though it were standing still. This vising means may be of mechanical or optical type, it being required that whether the glimpses of the rapidly moving web be through a mechanical shutter slit or a light 10 flash, synchronization or sufficient instantaneity be provided to give the optical result of a standstill view. In practice I prefer a light-flash arrangement, since by this it is possible to attain a desirable degree of illumination at the same 15 time. This may involve for instance a source of illumination 10 which may be a neon tube of white light character preferably, the light being mounted in a carrier 11 close to the traveling face of the paper web. Associated with the light-source is a 20 viewing tube 12 which for convenience may be L-shaped with a reflecting mirror 13 to direct the light rays to the eye of the operator at the observing-end 14. The eye piece may include magnifying lenses, or not, as desired. With this, as so far 25 described, it is readily understood that the operator standing at a point alongside the machine can view the rapidly moving paper web in the machine as though he were right over it. The light and the viewing tube are mounted on carriage- 30 means allowing accuracy of positioning, and this may include for instance suspending-brackets 15 extending from a suitable point of mounting above, and angular-adjustment brackets 16 pivoted to the latter and provided with arcuate slot 35 and clamping-nut adjustment means 17 intermediary, whereby the tube 12 and light 11 may be brought into desired angular adjustment with respect to the paper web P. Fore and aft adjustment is provided by a rack and pinion 20, 21, interposed between the bracket members 16 and the viewing tube 12, the latter being carried by holding strips 22 secured to a slide 23 which is mounted on the lower extension 24 of carriage members 25. The carriage members 25 travel on 40 guide bars 26 extending across in front of the paper web, and adjustment of the slide is had by a hand-wheel 27 and screw-threaded shaft 28 taking through the carriage members 25, whereby on turning the hand-wheel the mounting of the 45 light and viewing tube is moved in adjustment across the face of the paper web. Adjustment for distance is accomplished, as necessary, by the hand-wheel 30 operating the slide 23 through 50 the intermediary of the pinion 21 and rack 20. 55

The light-source 10, where of neon tube character, may be actuated by a flashing circuit comprising a secondary winding 33 of a transformer T whose primary winding 34 is supplied by a suitable 5 source of low potential current, for instance a battery 35. The transformer T and battery 35 may conveniently be placed upon the shelf s above the light and tube mounting. In circuit also with the primary winding and the current source is a commutator 36 which may comprise a body of insulation and a commutator bar 37 of copper or other suitable metal, arranged to be contacted by a pair of brushes 38, 39, carried on a brush holder 40. A convenient switch, as a double pole single throw 10 switch 41 serves to control the circuit. The commutator brushes 38, 39 may be of rod-form, of carbon or graphite composition, and with a spring 42 suitably arranged, constant contact with the commutator is assured. The commutator 36 is 15 carried by one of the shafts in the machine, such as to give properly timed contact for the closing of the circuit to produce the light flash upon the rapidly moving impressed paper web. In the form shown, the commutator is mounted on the shaft of 20 one of the cutter rolls 4.

In operation, the web of paper is fed through the series of printing rolls A, B, C, and the impressing or impression surfaces at A, B, C, for example, may apply successive color impressions, 30 as in the three-color process, and the impression surfaces at D, E, may apply black, as printing, etc., the entire assembly then providing colored illustrations and printed text. With the paper web thus subjected to successive impression-applying surfaces, the operator views it in its rapid motion, as he sights through the eye piece 14 of the vising-tube. At the same time, the commutator bar 37 of the commutator on the cutter-roll is making rapid contact with brushes 38, 39, thereby completing the circuit of the primary winding of the transformer, and correspondingly providing impulses in the secondary circuit to the light-tube 10. The voltage here may be of any suitable order, for instance 15,000 40 volts. If conveniently-located regulating means be close at the hand of the operator, he is thus in a position to regulate the register of the successive impression-applying rolls. For example, a desirable means for this may comprise adjustable slack-rolls 50, 51, between successive impression-applying cylinders. With these, the paper web threads over the rollers 50, 51, such as to provide a variable amount of slack between the successive printing cylinders, and by adjusting the angular position of roller 50 with respect to roller 51, more or less of the slack may be used, and correspondingly the paper web may be advanced or retarded with respect to the succeeding impression-applying surface, and thus 50 the point of application may be brought into accuracy of register. With a swing mounting of roller 50, as for instance on swing-arms 52, and a hand-wheel 53 controlling a screw-threaded stem 54 taking into a nut 55, the angular position of the roller 50 may be simply and accurately controlled.

It is thus unnecessary to wait until the finished product has gone clear through the machine before checking and adjusting the register. Rather, 70 this may be accomplished as the web travels along from the successive impression-applying surface, and irrespective of the speed, immediate and accurate register-adjustment may be made with convenience by the operator.

75 Other modes of applying the principle of the

invention may be employed, change being made as regards the details described, provided however, the features set forth in any of the following claims, or the equivalent of such, be employed.

I therefore particularly point out and distinctly claim as my invention:—

1. In printing machinery having a series of cylinders for applying ink impressions in succession to a travelling web of paper and having means for regulating said travelling web so as to obtain accurate register of said impressions, viewing means for obtaining a standstill view of said web to ascertain the register of the printed impressions, said viewing means including means for flashing light on the web and means in synchronism with the speed of travel of said web for providing the flashes, said viewing means being located in operating reach of said regulator means.

2. In printing machinery having a series of cylinders for applying ink impressions in succession to a travelling web of paper and having means for regulating said travelling web so as to obtain accurate register of said impressions, folding and cutting means over which the printed web runs, means for obtaining a standstill view of said web to ascertain the register of the printed impressions and including means for flashing light on the web, and a commutator connected with said folding and cutting means for timing the flashes of light with the travel of the web.

3. In printing machinery having a series of cylinders for applying ink impressions in succession to a travelling web of paper and having means for regulating said travelling web so as to obtain accurate register of said impressions, folding and cutting means over which the printed web runs, means for obtaining a standstill view of said web to ascertain the register of the printed impressions, including means for flashing light on the web and means operating in timed relation with said folding and cutting means and having a controlling-connection to said light-flashing means for timing the flashes of light with the travel of the web.

4. In printing machinery having spaced apart longitudinally extending framing elements and a series of cylinders transversely mounted therebetween for applying ink impressions in succession to a travelling web of paper and having means for regulating said travelling web so as to obtain accurate register of said impressions, folding and cutting means over which the printed web runs, means for intermittently flashing light on the web, means for timing the flashes of light with the travel of the web, a controlling-connection between said timing means and said light-flashing means, and a viewing tube sighting upon the travelling web between said cylinders and said folding and cutting means.

5. In printing machinery having spaced apart longitudinally extending framing elements and a series of cylinders transversely mounted therebetween for applying ink impressions in succession to a travelling web of paper and having means for regulating said travelling web so as to obtain accurate register of said impressions, folding and cutting means over which the printed web runs, means for intermittently flashing light on the web, means for timing the flashes of light with the travel of the web, a controlling-connection between said timing means and said light-flashing means, and a sighting tube with one end facing the web and the other end extending

angularly out as an eye piece accessible laterally of said framing elements.

6. In printing machinery having spaced apart longitudinally extending framing elements and a series of cylinders transversely mounted therebetween for applying ink impressions in succession to a travelling web of paper and having means for regulating said travelling web so as to obtain accurate register of said impressions, folding and

10 cutting means over which the printed web runs,

means for intermittently flashing light on the web, means for timing the flashes of light with the travel of the web, a controlling-connection between said timing means and said light-flashing means, a sighting tube with one end facing 5 the web and the other end extending angularly out as an eye piece accessible laterally of said framing elements, and means for adjusting said viewing tube with respect to the web.

WALTER E. HAMLIN. 10
